Patented Nov. 2, 1965

202,693

COMBINATION CHILD'S TRAINING CHAIR AND SEAT

Leger Salvy, 170 Westminster St., Oyonnax, France

Filed Nov. 24, 1964, Ser. No. 82,759

Term of patent 7 years

(Cl. D4—5)

FIG. 2

FIG. 3

FIG. 4

FIG. 5

FIG. 6

FIG. 1 is an exploded view of a combination child's training chair and seat, showing my new design.

FIG. 2 is a front elevation thereof, the substantially flat cover being omitted for the convenience of illustration.

FIG. 3 is a side elevation thereof.

FIG. 4 is a top plan view thereof.

FIG. 5 is a rear elevation thereof.

FIG. 6 is a bottom plan view thereof.

I claim:

The ornamental design for a combination child's training chair and seat, as shown and described.
